(57) **CLAIM**

The ornamental design for a bench center portion, as shown and described.

DESCRIPTION

FIG. 1 is a top view of the bench center portion of the present invention.

FIG. 2 is a bottom view of the bench center portion of the present invention.

FIG. 3 is a front view of the bench center portion of the present invention. The back view is identical and thus is not shown; and,

FIG. 4 is a side elevational view, the opposite side being identical thereto.

The broken lines are for environmental purposes only and form no part of the claimed design.
